UNITED STATES PATENT OFFICE.

BUTLER McMOORE, OF ARGENTA, ARKANSAS.

ICE-BOX FOR AUTOMOBILES.

1,230,914.

Specification of Letters Patent. Patented June 26, 1917.

Application filed October 5, 1916. Serial No. 123,877.

To all whom it may concern:

Be it known that I, BUTLER McMOORE, a citizen of the United States, residing at Argenta, in the county of Pulaski, State of Arkansas, have invented certain new and useful Improvements in Ice-Boxes for Automobiles; and I do declare the following to be a full, clear, and exact description of the invention, such as will enable others skilled in the art to which it pertains to make and use the same.

My invention relates to improvements in ice boxes or containers, and more particularly to an ice box adapted for use on an automobile or other vehicle for receiving and keeping food and other articles cool.

The invention consists in the several features and in the construction, combination and arrangement of features as more fully 20 hereinafter described and claimed.

The invention has for its object to provide an ice box or container which can be secured to an automobile, preferably on the running board thereof, in such a manner that it will 25 occupy very little space, be very convenient and keep the articles therein in a cool and sanitary condition.

It further has for its object to provide an ice box which will not only keep the 30 articles cool therein, but will filter, cool and furnish drinking water.

It further has for its object to provide an ice box which is simple, durable and inexpensive in construction, easy and convenient 35 to use and attractive in appearance.

It further has for its object to provide an ice box which is capable of being securely and easily attached to an automobile or other vehicle in such a manner that it will not be 40 come detached by the motion of the same and at the same time be readily detachable when desired.

It further has for its object to provide an ice box which will carry a maximum amount 45 of ice, and other articles such as ice cream, ginger pop, soda, coco cola, ginger ale, sarsaparilla, milk, sandwiches, etc. and will occupy a minimum amount of space.

Referring to the drawings:—

50 Fig. 1. is a side view of the ice box and a portion of the running board of an automobile showing the ice box in place thereon.

Fig. 2. is a top plan view.

55 Fig. 3. is a vertical section taken through the ice and filter compartments.

Fig. 4. a top plan view partly in section with the lid or cover of the ice box thrown back.

In the drawings in which like reference characters denote like parts throughout the several views, 1 represents the ice box, made of any suitable material and especially adapted for use on automobiles, which comprises four double walled sides 2 having packing 3 therebetween and a hinged lid or 65 cover 4 all of which are of the well known construction.

The inside of the ice box is divided into three compartments, a compartment 5 to contain ice 6, a compartment 7 to contain 70 an ice cream freezer 8 and other articles and a compartment 9 adapted to contain a filter.

The ice box is provided with an inclined floor or bottom 11, preferably inclined from front to rear thereof, which forms the floor 75 of the three compartments before mentioned.

Just below the bottom, 11 is another inclined bottom 12, inclined in a reverse direction from the floor or bottom 11, and having downwardly inclined portion 13 at 80 the front, the space between the floors or bottoms 11 and 12 forming a filtered ice water chamber 14 for drinking water.

By having the floors or bottoms 11 and 12 inclined the water is prevented from settling 85 or standing and becoming stagnant and is caused to run or flow toward the faucets where it can all be drawn off, as often as desired, and in this way the ice box can be kept in a clean and sanitary condition. 90

A faucet 16 is provided which is inserted through the front wall of the ice box into the water chamber to afford means for drawing or dispensing drinking water and a faucet 15 is provided which is inserted through 95 the rear wall of the ice box, into the ice compartment to afford means for drawing off the waste water from the ice.

A filter tube or cylinder 17 is provided, adapted to be inserted in the filter compartment 9 and contain unfiltered water and is provided with a suitable filtering medium 18 at the bottom and at the top with a drinking cup 19, and a hole or passage 20 is provided in the inclined bottom, 11 under the 100 filter tube, to allow the filtered water from the filter to pass into the water chamber 14. The top of the filter tube 17 and the bottom of the cup 19 placed thereon are substantially in alinement with the upper edge of 110

the ice box and the cover 4 is adapted to contact with the bottom of the cup 19 and retain it in position on the filter tube.

The upper portion of the ice compartment 5 is provided with a number of ledges or cleats 21 on which screen wire shelves 22 are adapted to be mounted on which lunches and other articles may be placed.

Flanges 23 project laterally from each side 10 of the bottom of the ice box and are adapted to be secured to the running board of an automobile by means of bolts or screws 24.

The ice box may be loaded or filled with ice and provisions before being secured to 15 the running board of an automobile or it may be secured first and then loaded as is found most convenient under existing circumstances.

I do not wish to be understood as limiting myself to the specific details of construction and arrangement as herein described and illustrated, as it is manifest that variations and modifications may be made 20 in the features of construction and arrangement, in the adaptation of the device to various conditions of use, without departing from the spirit and scope of my invention and improvements. I therefore reserve the right to all such variations and modifications 25 as properly fall within the scope of my invention and the terms of the following claims.

What I claim is:—

1. In an ice box for automobiles, a cover 35 therefor, an ice compartment having an inclined floor, a filter compartment within the ice box and situated back of said ice compartment and provided with an inclined floor with a hole or passage therethrough, a 40 filter tube or cylinder supported entirely or wholly within said filter compartment and provided with a filtering medium, a cup below the upper edge of the ice box adapted to fit over the top of said filter tube or cylinder 45 and form an air and liquid tight closure and held in place by the cover of the ice box, an

inclined floor below the inclined floors of the ice and filter compartments, a filtered water receiving chamber between said inclined floors and means for withdrawing water 50 from said ice and filtered water compartments.

2. In an ice box for automobiles, an ice compartment having an inclined floor, a filter compartment within the ice box and back 55 of the said ice compartment and provided with an inclined floor with a hole or passage therethrough, a filter tube or cylinder supported within said filter compartment provided with a suitable filtering medium, an 60 imperforate cup adapted to fit over the top of said filter tube or cylinder and substantially in alignment with the upper edge of the ice box, a cover for said ice box adapted to contact with said imperforate cup and 65 retain it in position on the filter tube or cylinder, a filtered water receiving compartment communicating with the filter compartment and means for allowing the withdrawal of water from the filter and ice compartments.

3. In an ice box for automobiles, a filtered water compartment, an ice compartment having an inclined floor, filter and ice cream 70 freezer compartments back of said ice compartment and within the ice box each having an inclined floor, a passage through the floor of the filter compartment communicating with the filtered water compartment, a filter tube or cylinder within said filter compartment provided with a filtering medium, an 75 imperforate cup adapted to fit over the top of said filter tube and form a water and dust tight closure, a cover for said ice box adapted to contact with said imperforate 80 cup, on the closing of said cover, and thereby retain the said cup in position on the top of the filter tube or cylinder and means for allowing the withdrawal of water from the ice and filtered water compartments.

BUTLER McMOORE.
